ABRASIVE MITT

Herman Greenwald, Brooklyn, N. Y., assignor to
 Herman Greenwald and Emanuel Koenig, New
 York, N. Y., doing business as Hygrade Novel-
 ty Co.

Application June 19, 1936, Serial No. 86,097

5 Claims. (Cl. 15—227)

This invention relates to a new and useful improvement in abrasive mitts.

Broadly, it is an object of my invention to provide an abrasive holder which is convenient, inexpensive and practical for cleaning and polishing all kinds of pots, pans, kettles and kitchenware at the same time protecting the hand of the user from water, harmful scouring powders, soaps, grease and dirt.

10 Another object of my invention is to produce an improved holder for steel wool, copper wool, cotton waste, or the like, having means for gripping such cleaning material so that various types of articles may be cleaned or polished, such as, kitchen utensils, woodwork, floors, furniture and other similar articles.

Another object is to provide a holder for steel wool, or the like, which will prevent such materials from contacting the fingers or hand of the 20 user, thus reducing the danger of infection that may be caused by the abrasive material or the article to be cleaned.

Another object is to produce a hand covering which will keep the hand dry during the cleaning 25 or polishing process, thereby preventing unsightly, roughened, reddened and chapped hands.

Still another object is to produce an abrasive holder which is simple to manufacture, inexpensive, effective and in which the abrasive used 30 can be readily replaced or readjusted.

With these and other objects in view, as will be more fully set forth hereinafter, my invention consists in the novel construction, combination of elements and arrangements of parts which will be 35 exemplified in the operation and construction herein described in the following specification and illustrated in the accompanying drawing.

The invention will first be described in connection with the accompanying drawing wherein 40 similar reference characters are used to designate corresponding parts throughout the several views and more specifically defined and indicated in the appended claims.

45 Attention is directed to the drawing, in which: Fig. 1 is a front elevation, showing the inside or palm view of the abrasive mitt containing the pocket for the abrasive.

Fig. 2 illustrates the reverse side thereof, 50 equivalent to the back of the hand, showing the attaching or retaining means for holding the abrasive.

Fig. 3 is a side elevation of the abrasive mitt, and

55 Fig. 4 is an enlarged transverse section, taken

through the mitt containing the abrasive, as indicated by the line 5—5 in Fig. 1.

Referring to the drawing in Fig. 1, 10 represents a section of a waterproof material which fits over the palm and fingers of the hand and the wrist. 5 This material may be of oil cloth, a rubber coated fabric or other waterproof material. A pocket 11, preferably of the same material as section 10, is provided across the finger portion of the hand and along the entire width of the mitt. This pocket 10 has an opening at both ends so that an abrasive 12, or other cleaning material, may be placed within said pocket 11, and drawn through the opening 13, at the upper end of the finger portion.

A back section 14, preferably of the same waterproof material as section 10, is provided to cover the back of the hand. Hooks 15 and 16 are firmly attached to a tape 17, said tape being stitched or cemented to the upper end of the back section 14.

Sections 10 and 14 and pocket 11 are securely 20 held together by means of binding strips, said binding strips being either stitched or firmly cemented down. Pocket 11, is edged with similar binding strips 19 and 20 and the bottom of the back section 14 with binding strip 21. Section 25 10 also contains a binding strip 24 at the thumb opening 23.

Sections 10 and 14 are not joined together at the wrist section, as shown at 22, thus providing an opening to receive the hand as pictured by dotted 30 line 26. A thumb opening 23, is provided through which the thumb is inserted when the mitt is placed in position for use. While I only picture a right handed mitt with one thumb opening, I do not wish to be understood as confining my invention to a right hand alone. 35

Any type of abrasive, such as steel wool, copper wool, cotton waste, or the like, may be used as the abrasive, cleaner or polisher and said abrasive is placed within the pocket 11, drawn through the 40 opening 13, near the top, over the top of the mitt and is then attached by placing the abrasive through hooks 15 and 16. Hooks are my preferred means of attaching the abrasive or polishing material. Section 10, may be provided with an eyelet 25, placed near the wrist portion so that the mitt may be readily hung upon the hook. 45

Referring to Fig. 4, it will be readily seen that the abrasive 12, lies between pocket section 11 and palm section 10, and the fingers 27, lie between palm section 10 and the back section 14. 50

In accordance with the provisions of the patent statutes, I have described my invention together with the constructions which I now consider to represent the best embodiment thereof, but I de- 55

sire it understood that my invention is not confined to the particular forms shown and described, the same being merely illustrative, and that the invention can be carried out in other ways without departing from the spirit of my invention, and therefore, I claim broadly the right to employ all equivalent instrumentalities coming within the scope of the appended claims, and by means of which objects of my invention are attained, and new results accom'^{pli}ed, as herein set forth, as it is obvious that the particular embodiments as herein shown and described are only some of the many that can be employed to attain these objects and accomplish these results.

15 16 I claim:

1. An abrasive mitt in the class described, comprising a back and front section bound together, a wrist opening at the lower end and a finger portion at the upper end, a thumb opening formed 20 in a side edge thereof, a pocket across the front section of the finger portion, said pocket being open at the finger portion and the lower end to hold a flexible abrasive strip, part of said abrasive strip being drawn through the opening at the 25 finger portion.

2. An abrasive mitt of the class described, comprising a back section and a front section, a thumb opening in a side edge thereof and a wrist portion at the lower end and a finger portion at 30 the upper end, said front and back sections being bound together at their marginal edges, a wrist opening at said wrist portion, a pocket on said mitt across the front section and attached to said marginal edges, said pocket being open at the said 35 finger portion and its opposite end, whereby a flexible abrasive strip may be placed within said pocket and partly drawn through the opening at the finger portion and over the upper part of the back section, and attaching means at the finger 40 end of the back section for holding said abrasive strip in place.

3. An abrasive mitt of the class described, comprising a back and front section bound together, said sections having a wrist and finger end, an opening at the wrist end for the hand, a thumb opening formed in a side edge thereof, a pocket to hold one end of a flexible abrasive strip, said pocket being attached across the finger end of the front section and open at the finger end and the end nearest the wrist end, and a tape attached to the finger end of the back portion, said tape 10 containing hooks for holding the other end of said flexible abrasive strip in position.

4. An abrasive mitt of the class described, comprising a back and front section bound together, said back and front sections having a finger end 15 and wrist end, an opening at said wrist end to admit a hand, a thumb opening formed in a side edge thereof, a pocket for a flexible abrasive strip attached to the finger end of the front section having an opening at the finger end and the 20 end nearest the wrist end, part of said flexible abrasive strip being drawn through said pocket opening at the finger end and over part of the finger end of the back section and fastened to hooks attached to the finger end of the back 25 section.

5. An abrasive mitt of the class described, comprising a back and front section bound together, a wrist opening on one end, a thumb opening formed in a side edge thereof, a pocket attached 30 to the front section at the finger end, said pocket being open both at the finger end and the end opposite said finger end for holding a flexible abrasive strip, said abrasive strip being drawn through said pocket opening at the finger end 35 and over part of the back section, said abrasive being fastened to hooks attached to said back section.

HERMAN GREENWALD. 40
